FLUID SYSTEM CONTROL

Archibald H. Davis, Jr., Moline, Ill., assignor to
 American Machine and Metals, Inc., New York,
 N. Y., a corporation of Delaware

Application June 9, 1941, Serial No. 397,170

7 Claims. (Cl. 60—52)

This invention relates to hydraulic driven testing apparatus in which the movable platen is to move toward or away from a fixed head at a uniform rate.

This requires that the rate of motion of the ram be uniform within closer limits than is required in most other hydraulic equipment. This uniformity of motion must be maintained even though the resistance of the specimen and the load on the machine vary sharply.

Though the invention is primarily applicable to universal testing machines the invention is not limited thereto but includes all hydraulic plunger applications in which uniformity of motion is to be secured despite variable resistance.

In the practice of this invention a cylinder is provided with a metering feed device giving a constant rate of liquid feed and a secondary supply from which measured additional liquid may be discharged into the system depending upon the load on the machine and the position of the ram in the cylinder.

The additional liquid may be discharged into the cylinder manually or, preferably, automatically as the pressure rises.

The amount discharged may be made to vary not only with the pressure change of the liquid but also with the amount of oil already in the cylinder of the testing machine.

At the beginning of the stroke, before the specimen creates much resistance, the pressure on the ram, and therefore the pressure on the oil, that is fed to the cylinder is low. As the resistance of the specimen increases, so will the pressure on the oil, and in commercial practice this pressure may rise to 3000# per square inch or more.

Various devices have been provided, the object of which is to feed the liquid, usually oil, at a constant metered rate regardless of the counter pressure of the ram. Applicant's earlier application on a Fluid system control filed March 22, 1941, Serial No. 384,692, shows such a control designed to feed liquid to the cylinder at a uniform rate.

Tests with machines equipped with metering controls that feed the oil at an absolutely uniform rate show that the rate of feed of the table decreases as the load is applied. The reason for this is that when the ram moves forward under low pressure, the space underneath the ram has been filled with oil at low pressure. Even though, under the increased resistance, the metering device delivers additional oil already compressed at the same rate as before some of that oil will be used to make up for the reduction in volume of the oil already in the cylinder due to the compression of the oil under the wide range of pressure used.

The tests have shown that, to secure uniform 60 lines.

motion of the ram we must feed at a faster rate than normal when the pressure in the system is rising and at a slower rate than normal if the pressure is falling.

5 In a standard universal testing machine, with a piston elevated 6" from the bottom of the cylinder, the volume of oil required to compress the 300 cubic inches of oil under the piston to 3000# is approximately .33 cubic inch. This 10 means that with an oil feed of .50 cubic inch per minute (corresponding to .01" per minute desired feed), and a specimen that loads the machine to full rating in one minute the .50 cubic inch of oil is divided into .33 cubic inch for compression of oil and .17 cubic inch for movement of the piston. The feed would be only .17/50=.0034" per minute instead of the .01 feed desired.

The difficulty cannot be eliminated by recalibrating the metering system so that an opening of the control valve that is marked .010" per minute actually passes oil enough to both cover that movement and to offset oil compression.

For if the next specimen loaded itself in two minutes instead of one minute the oil compression would be overcorrected, and if it took ten minutes the necessary correction would be only .033 cubic inch per minute so that one valve, for the same setting, would give us a feed of .010" for a one-minute loading and .016" per minute for a two-minute loading time.

The invention provides a second supply of liquid from which enough is discharged into the already metered supply to the cylinder to make up for the compression of the oil previously fed to the cylinder at the lower pressures.

This recognizes that the additional amount of oil is a function of the compressibility of the oil, of the volume of oil under the plunger at the time the test is to be made, and of the rise of pressure during the test.

The device may be manually operated at the right time or it may be made to automatically discharge the proper amount of oil into the cylinder as the pressure rises.

The object of the invention is to provide a universal testing machine or the like in which the ram will advance at a uniform rate, predetermined, regardless of varying resistance encountered.

A further object is to eliminate the effect of the compression of oil upon the rate of movement of a plunger where the feed of oil is maintained uniform.

55 A further object is to eliminate the effect of the increase in pressure of oil in a system to which the rate of addition of oil is uniform, correcting for the reduction of volume of oil under compression as well as the distension of oil supply

A further object is to provide a supplementary storage reservoir from which an amount of liquid approximately equal to that needed to offset the compression of the oil is automatically discharged into the cylinder.

A further object is to provide a device which will automatically correct for the compression of oil in the ram of the testing machine taking into account both the rate of change in pressure and the volume of the oil in the cylinder at the working range.

This compensator is intended for use in connection with a precalibrated rate of oil feed. If we had a slow speed and a uniform load over wide range, such as an extruding operation, the precalibrated speed would be maintained and require no correction. However, when, as in normal testing operations, the early portion of the stroke is merely to take up slack and apply the initial load and then the pressure rises up to the end of the test, the precalibrated speed will not be maintained during the latter, and the important part of the test, because some of the oil being supplied instead of being used to move the ram is used to make up for the compression of the oil which has already been supplied.

Figure 1 is a diagrammatic arrangement, partly in section, of a universal hydraulic testing machine equipped with a control constructed as disclosed in the above cited prior application and with the additional oil compression compensator which is the subject of this invention.

Figure 2 is an enlarged elevation, partly in section, of the oil compensator.

Figure 3 is a section of the compensator taken along line 3—3 of Figure 2.

The invention comprises a source of power generally indicated at 1, a pump generally indicated at 6, drawing liquid from a reservoir 8, and feeding through the device 23 designed to give a uniform flow for any given setting of the valve 52 to the cylinder of the machine generally indicated at 20. The machine is equipped with means for preventing leakage along the cylinder walls which do not impose frictional resistance in the manner explained in applicant's earlier application, Serial No. 334,333, filed May 10, 1940. This fluid packing is applied through the groove generally indicated at 17. The plunger 19 of the testing machine exerts pressure upon a specimen 60 in a universal machine of conventional type 100.

A cylinder generally indicated as 101 in Figure 2 contains liquid, which may be discharged through line 104 when the pressure under the ram overcomes a calibrated spring 128. This amount also takes into account the height to which the plunger has moved. This is accomplished by manually setting handle 136 in proper relation to scale 140.

When the test is completed and the pressure is released the spring 128 will automatically refill cylinder 101 preparatory to the next test to be performed.

1 is normally a motor shaft driving a multi-cylinder plunger pump 6 which draws liquid in through a check valve 7 and discharges through a check valve 12 liquid drawn from reservoir 8 into line 13. It is understood that oil under adequate pressure and in adequate volume may be supplied to main 13 in any manner desired as the pump does not form any part of the invention. Liquid under pressure is supplied through lines 14 and 16 to the fluid packing groove 17

referred to in the previous application on fluid packing.

Liquid under pressure is also supplied through line 15 to a pressure controller generally indicated at 23 which provides a uniform pressure differential across the manually adjustable controller valve 52 which feeds into a line 55 to space 20 in cylinder 18. The construction of this pressure reducer is shown in detail in Figure 1 of the fluid control application #384,692, previously referred to. The uniform pressure differential across valve 52 is obtained by controlling the discharge through bypass 42 which reduces the pump pressure to a predetermined amount above the pressure in line 55. This control is automatically accomplished by the pressure control at 23. The discharged oil passes into line 22 which collects the leakage from groove 21 and discharges through 10 into tank 8.

20 Summarizing, the pressure in lines 14, 15, 16, and fluid packing groove 17 will always be slightly above the pressure in line 55 and space 20. This amount will be just sufficient to give the desired rate of uniform discharge across the contraction imposed at valve 52. Through line 103 which connects with feed line 15, space 98 below the piston is under the same pressure as the supply side of valve 52. Normally this piston is in the position shown resting upon the piston extension 96. The upper side of this piston, space 97, discharges through line 104 into line 55. Accordingly, whenever piston 102 moves upwards a quantity of oil proportional to the amount of movement of piston 102 is discharged through line 104 into 55. This is in addition to that supplied through the metering valve 52.

The unit pressure on the under side of the piston 102 is higher than the unit pressure on the upper side of the piston. Also the area of 40 the upper side is smaller than the area of the lower side by the area of stem 108. Accordingly there will be a differential pressure tending to move piston 102 and its stem 108 upwards. This is resisted by pad 118 of a swinging lever 117.

This frame carries a slot 116, substantially an arc concentric with pivot 130 when the pad 118 is in its lowest position. On pivot 130 an arm 135 may be swung by handle 136. A carriage 50 126 slides along arm 135. It carries a roller 125 on a stud 119, the roller traveling in the arcuate slot 116 of lever 115. The carriage 126 is urged toward pivot 130 by a calibrated spring 128 which engages the carriage at 127 and the 55 end piece of the lever, 129, at 131. This spring is selected of such length and such resistance to elongate as is required. The initial stress will just offset the unbalance of forces on piston 102, just described, tending to lift the piston before 60 load is applied.

Assume that the lever 135 has been swung to the extreme left and the plunger 19 is at the bottom of the cylinder. The end of the lever moves along an arcuate scale 140 which is fastened by screws 141 to studs 142 upon the panel generally indicated at 99. The spring, which is shown of a fixed length but one end of which may be fastened adjustably to permit varying its effective length is under a tension just sufficient to prevent the rise of plunger 108 when the pressure under the ram of the machine is merely that corresponding to the weight of the table and its accessories being lifted. There will be no discharge from space 97 into line 104. 70 As the testing proceeds and the ram meets re-

sistance the pressure in line 104 will increase and the pressure in 103 will increase correspondingly. The difference between the unit pressures on the two sides of the piston has already been counterbalanced by the initial tension of spring 128. The increased pressure in line 103 acting over the difference in area between the two sides of the piston is not counterbalanced however and therefore the piston 102 will rise, somewhat increasing the tension on spring 108. This small movement of plunger 102 has discharged a small quantity of oil through line 104 to offset the compression of the oil already in the cylinder by the increased pressure at which the oil is now being delivered to the cylinder. It will be seen that the amount of liquid discharged from space 97 is directly proportional to the increased pressure in the cylinder.

The purpose of lever 135 permitting the movement of roller 115 in slot 116 is to give an increased movement to pad 118 and therefore an increased movement of plunger 102 for a given pressure in the cylinder, if desired, by moving the handle 136 a small distance to the right. Thus the amount of oil discharged can be increased and we can determine experimentally the point of the end of the lever on the scale 140 that will correct for the compression of the oil, not only in the cylinder but in the piping system when the piston 19 is at the bottom. It is clear that if the piston is part way up there will be more oil under the piston, more oil required to make the compressibility correction. Accordingly lever 135 will be moved further to the right to a point on the scale 140 which may be experimentally determined that will give the increased discharge of oil through 104 to make the correction.

In the arrangement shown in the drawing it is necessary to manually move lever 135 by scale 140 to correspond to the position of platen 150 as indicated by pointer 151 on vertical scale 152.

Since the position of lever 135 is related to the position of platen 150 on top of piston 19 it may be moved thereby by the use of a suitable system of levers and connecting rods so that the position of lever 135 will automatically correspond to the position of the platen.

In the ordinary test where the position of the piston corresponds to the adjustment of the platen to the specimen length, and the actual test extends over only a short vertical range, this procedure may be simplified by moving the lever 135 but once to the position corresponding to that at which the actual test load is applied.

If however the load increases over a considerable range of the stroke of plunger 19 lever 135 should be moved over the corresponding range of the scale in the same manner as it would had it been connected mechanically to the platen.

When the load is released from the specimen and the pressure in line 104 drops the extended spring 128 will automatically restore the parts to the condition shown in Figure 2 and therefore space 97 will draw in the same amount of oil discharged during the load application. Thus, at the beginning of each new test piston 102 is always in its lower position as shown. The device therefore corrects for the decompression of the oil as pressure is released, for instance, because of passing the elastic limit of the specimen, as well as for the compression as pressure is increased.

It will be evident that in attempting to correct for inaccuracies of the order of a fraction of a cubic inch of fluid there must be no leakage with-

in the correcting device. Accordingly, to prevent the loss of liquid along the stem 108, the upward extension 110 of the cylinder contains annular area 106. The groove 106 is connected by line 105 with the unmetered supply line 103. Therefore the pressure differential between groove 106 and space 97, as well as between spaces 97 and 98, is small. In practice this pressure differential is 50# per square inch, and the loss of liquid in a well fitted piston and plunger under such low pressure differential is negligible. Line 105 and groove 106 form a fluid packing of the same type shown in the earlier application and the loss of oil due to the high pressure drop between grooves 106 and 107 represents only the return of an indefinite and unimportant quantity of liquid from the unmetered supply line 105 through 107 back to the sump.

It will be understood that the parts are so designed that when the plunger of the testing machine is at maximum load and at maximum stroke and lever 135 moves toward the right the movement of piston 102 will not quite equal the length of stroke permitted by cylinder 101 and that for all other conditions of testing the stroke of piston 102 will be less.

I claim:

1. A hydraulic system comprising, in combination, a source of liquid supply, a pressure chamber, a conduit leading from the source of supply to the pressure chamber, a metering device in said conduit, a liquid container for adding additional liquid to the pressure chamber to offset the loss of volume of liquid in the chamber when the pressure increases, the container including a differential piston, a connection from the source of pressure to one end of the container tending to drive the differential piston forward, a connection from the opposite side of the differential piston leading from the container to the chamber and means offering increasing resistance to the movement of the differential piston so that the volume of liquid ejected corresponds to the movement of the differential piston and the change of pressure in the system.

2. In combination, a cylinder, a plunger movable therein, a source of supply of fluid under pressure, a conduit leading from the fluid supply to the cylinder, a metering valve in the conduit, a pressure controller ahead of the metering valve, a discharge opening in the conduit controlled by the pressure controller for diverting a part of the fluid supply, the pressure controller being adapted to maintain a constant differential across the metering valve by varying the proportion of the fluid supply that is diverted; a supply chamber for additional fluid, a floating piston therein, a connection from one side of the metering valve to one end of the supply chamber, a connection from the other side of the metering valve to the other side of the supply chamber, a spring stressed by the movement of the piston in the chamber, the spring permitting further movement of the piston and further discharge of additional fluid into the cylinder only as the pressure on one side of the metering valve increases.

3. A hydraulic system comprising, in combination, an expandible chamber, a source of liquid under pressure, a conduit leading from the source to the chamber, a metering device in said conduit, means for compensating for the change of volume of the liquid already metered due to changes in the pressure on the liquid in the chamber by adding or withdrawing a measured quantity of additional liquid to the chamber comprising a

tank, a differential piston therein, conduits connecting one side of the piston to one side of the metering device and the other side of the piston to the other side of the metering device, the pressures upon the differential piston areas creating a force that varies with the pressure in the chamber and tends to move the piston, means including a spring progressively stressed as the piston moves to balance said force, the movement of the piston required to secure said balance determining the quantity of compensating liquid added to the chamber.

4. A hydraulic system comprising, in combination, an expansible chamber, a source of liquid under pressure, a conduit from the source to the chamber, a metering device in said conduit, means for compensating for the change of volume of the liquid already metered due to changes in the pressure of the liquid in the chamber by adding or withdrawing a measured quantity of additional liquid to the chamber comprising a tank of liquid, a differential piston therein, conduits connecting one side of the piston to one side of the meter and the other side of the piston to the other side of the meter, the pressures upon the differential piston areas creating a force that varies with the pressure in the chamber, a base on which the tank is mounted, a lever pivoted on the base, one end bearing against the piston, a cam surface on the lever, an arm pivoted on the base, a slider bearing on the cam that is free to move along the arm, a spring urging the slider against the cam and thereby exerting pressure on the plunger, a scale on the base over which the arm moves calibrated for the approximate volume of the chamber in use whereby the quantity of fluid delivered from the tank for a given pressure change in the chamber can be varied according to the size of the expansible chamber by setting the arm.

5. A hydraulic system comprising, in combination, an expansible chamber, a source of liquid

under pressure, a conduit from the source to the chamber, a metering device in said conduit, means for compensating for the change of volume of the liquid already metered due to changes in the pressure of the liquid in the chamber by adding or withdrawing a measured quantity of additional liquid to the chamber comprising, a tank of liquid, a differential piston therein, conduits connecting one side of the piston to one side of the meter and the other side of the piston to the other side of the meter, the pressures upon the differential piston areas creating a force that varies with the pressure in the chamber, a base on which the tank is mounted, a lever pivoted on the base, one end bearing against the piston, a cam surface on the lever, an arm pivoted on the base, a slider bearing on the cam that is free to move along the arm, a spring urging the slider against the cam and thereby exerting pressure on the plunger, a scale on the base over which the arm moves calibrated for the approximate volume of the chamber in use whereby the quantity of fluid delivered from the tank for a given pressure change in the chamber can be varied according to the size of the expansible chamber by setting the arm.

6. In claim 3, said last-named means including manually adjustable means for varying the amount of piston movement that corresponds to a given spring deflection.

7. In claim 3, said last-named means including a pivoted lever, one end of the lever resisting movement of the piston, a spring one end of which is anchored, the other bearing upon the lever, means for varying the distance of the spring end bearing upon the lever from the pivoted end of the lever.

ARCHIBALD H. DAVIS, JR.
